DESIGN FOR A COLLAR HOLDER

Frederick A. Bullock, Attleboro, Mass., assignor to Dolan & Bullock Company, Providence, R. I., a corporation of Rhode Island

Application September 13, 1939, Serial No. 87,177

Term of patent 7 years

To all whom it may concern:

Be it known that I, Frederick A. Bullock, a citizen of the United States, residing at Attleboro, in the county of Bristol and State of Massachusetts, have invented a new, original, and ornamental Design for a Collar Holder, of which the following is a specification, reference being had to the accompanying drawing, constituting a part thereof.

Fig. 1 is a front elevation of a collar holder showing my new design; and

Fig. 2 is a side elevation of the collar holder shown in Fig. 1.

I claim:

The ornamental design for a collar holder, substantially as shown.

FREDERICK A. BULLOCK.
